O. J. HEBERT

WASHBOARD

Filed July 24, 1923

INVENTOR.
Octave J. Hebert,

BY

Geo. P. Kinnane,
ATTORNEY.

UNITED STATES PATENT OFFICE.

OCTAIVE J. HEBERT, OF NEW IBERIA, LOUISIANA.

WASHBOARD.

Application filed July 24, 1923. Serial No. 653,582.

To all whom it may concern:

Be it known that I, OCTAIVE J. HEBERT, a citizen of the United States, residing at New Iberia, in the parish of Iberia and State of Louisiana, have invented certain new and useful Improvements in Washboards, of which the following is a specification.

This invention relates to wash boards and has for its object to provide, in a manner as hereinafter set forth, a wash board including a rubbing element formed from a flat rectangular base having each of its faces provided with spaced transverse ribs constructed of a single length of wire of suitable diameter anchored in one side edge and anchored in and secured to the other side edge of the base thereby when the wire is set up to provide both faces of the base with the transverse ribs a rubbing element is formed on each of its faces with a ribbed surface against which the clothes are rubbed when the wash board is used.

A further object of the invention is to provide a wash board, in a manner as hereinafter set forth, with a rubbing element and means connected with said element to form a soap holder at each side of the head of the wash board, and with said means and element constructed to provide a plurality of drainage openings for each holder at the bottom of the latter.

A further object of the invention is to provide a wash board, in a manner as hereinafter set forth, with a rubbing element extended into a pair of supporting legs, with means carried by the legs and engaging in the sides of the rubbing element for securing said legs and rubbing element together, and with means for coupling the legs together to hold the rubbing element and which in connection with the means for securing the rubbing element to the legs will rigidly secure the legs and element together, and further with said coupling element preventing the spreading of the legs with respect to each other when the wash board is used.

Further objects of the invention are to provide a wash board, in a manner as hereinafter referred to, which is simple in its construction and arrangement, strong, durable, compact, thoroughly efficient in its use, readily assembled and inexpensive to manufacture.

With the foregoing and other objects in

view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a perspective view of a washboard in accordance with this invention.

Figure 2 is a section on line 2—2, Figure 1.

Figure 3 is an edge view, broken away, of the rubbing element.

Figure 4 is a section on line 4—4, Figure 1.

Figure 5 is a section on line 5—5, Figure 3.

Figure 6, is a section on line 6—6, Figure 2.

Referring to the drawings in detail, a wash board in accordance with this invention comprises a pair of supporting legs 1, 2, and each of which has its inner face formed with a lengthwise extending rectangular pocket 3. The pocket 3 starts from a point removed from the upper end of the leg and terminates at a point removed from the lower end of the leg. The leg 1, as well as the leg 2, has its upper end provided with a centrally disposed transversely extending tongue 4.

The upper edge of the leg 1, as well as the upper edge of the leg 2, provides a seat for the top bar 5 of a wash board and said bar 5 is of a width, when seated on the upper ends of the legs 1, 2, to project from each edge of a leg as clearly shown in Figure 2. Each end of the top bar 5 is provided with a vertically disposed groove 6 and into each groove 6 extends a tongue 4, as shown in Figure 1. The size of the tongues 4 with respect to the width of the groove 6 is such that tongues 4 will frictionally engage the walls of the grooves 6, whereby the bar 5 is secured to the legs 1, 2, but for further fixedly securing the bar 5 to the upper end of the legs 1, 2, securing devices, as indicated at 7 are employed.

The leg 1, as well as the leg 2, has the upper portion of its inner face formed centrally thereof with a lengthwise groove, as

indicated at 8, and said groove 8 extends from the top wall of the pocket 3 to the top edge of the leg, and having its ends extending into the groove 8, as well as its top edge 5 abutting against the inner face of the top bar 5, is a partition member 9, which in connection with a pair of transversely extending angle-shaped strips 10 and a rubbing element, to be presently referred to, as well 10 as further in connection with the legs 1, 2, and the top bar 5, provides a pair of soap holders as indicated at 11, 12, near the head of the wash board.

Arranged between the legs 1, 2, as well as 15 being connected therewith, is a rubbing element which consists of a rectangular flat base 13 of a length equal to the length of a pocket 3. The thickness of the base 13 is such as to snugly fit the side walls of a 20 pocket 3, as shown in Figure 4. Each side marginal portion of each face of the base 13 is provided with a set of spaced parallel horizontally extending grooves gradually increasing in depth towards a side edge of 25 the base. The horizontally extending grooves in one side marginal portion of each face of the base terminate into transverse grooves, to be presently referred to, formed in one side edge of the base. The other 30 horizontally extending grooves in the other side marginal portions of the base terminate into inclined grooves, to be presently referred to, formed in the other side edge of the base. The transverse side edge grooves 35 as well as the inclined side edge grooves gradually increase in depth from the center thereof towards each end. One side edge of the base 13 is formed with spaced grooves 14, which are transversely disposed with respect to said edge and are semi-oval shaped in plan, as shown in Figure 5, and of a 40 length to terminate in a pair of marginal grooves on opposite faces of the base 13. The other side edge of the base 13 is formed with grooves 15, disposed at an inclination, and in plan are semi-oval shaped in contour and each is of a length to extend from a 45 lower marginal groove on one face to an upper marginal groove on the other face of the base 13, as shown in Figure 5. The grooves 14 are spaced equidistant from each other and a similar arrangement is set up with respect to the grooves 15. Each groove 50 14 merges into a pair of marginal grooves arranged on opposite faces of the base. Each groove 15 extends at an acute angle with respect to a lower marginal groove on one face and merges into an upper marginal groove on the other face of the base. 55 Each face of the base 13 is provided with spaced transverse ribs 16, and which are formed from a single length of wire of the desired diameter and said wire is wrapped around the base 13, extended through the 60 grooves 14 and through the grooves 15, and 65

said wire which is indicated at 17 has its lower terminal portion looped, as at 18, and extending through said looped portion is a yoke-shaped securing device, which also overlaps the bend 20 in the wire 17 which is mounted in the lowermost groove 15. The upper terminal portion of the wire 17 is provided with a loop 21 through which extends the angularly disposed terminal 22 of the said upper terminal portion of the 75 wire 17. The wire 17 at the upper end of the base 13 is seated in the upper groove 14 and also in the upper groove 15. The manner in which the terminal portions of the wire 17 are secured to the base 13, is clearly 80 shown in Figure 3.

The strips 10 are positioned against the base 13 at the upper end thereof, as shown in Figure 2, and said strips are connected to the base 13 by suitable securing devices 85 23. The top edge of the base 13 is formed with a groove 24 which constitutes a seat for the bottom edge of the partition member 9. The said bottom edge 25 of said partition member corresponds in contour to the shape of the groove 24. The base 13, at its top, at each side thereof, is provided with a plurality of angle shaped grooves 26, which oppose vertical grooves 27 formed on the inner face of the strips 10, and said grooves 90 26, in connection with the grooves 27 provide each of the soap holders at the bottom thereof with a plurality of drainage openings.

The base 13 extends into the pockets 3, as 100 shown in Figure 4, and extending through the legs 1, 2, and engaging in the side edges of the base 13, are hold-fast devices 28 for connecting the base 13 with the legs.

To prevent the spreading of the legs 1, 2, 105 with respect to the rubbing element, a coupling element is employed for connecting the legs 1, 2 together and said coupling element or member is arranged against the lower edge of the base 13. The said coupling element or member consists of a length of wire 29 of the desired diameter and which is seated in a groove 30 formed in the bottom edge of the base 13. The wire 29 extends through each of the legs as indicated at 110 31 and is then bent upwardly to seat in a groove 32, formed on the outer face of each of the legs and then extended into the legs and by this arrangement the legs 1, 2, are 115 coupled together to prevent the spreading 120 thereof when the wash board is used.

From the foregoing description taken in connection with the accompanying drawings a rigid construction of wash board is set up 125 having a pair of rubbing surfaces and with such surfaces formed of a base provided with ribs constructed from a single length of wire secured to and anchored in the base, and by this arrangement an unusually durable rubbing surface is provided, and al- 130

though the preferred embodiment of the invention is as illustrated and described, yet it is to be understood that changes in the details of construction can be resorted to which come within the scope of the claims hereunto appended.

What I claim is:—

1. A washboard comprising a rubbing element consisting of a flat rectangular base of substantial thickness having each side marginal portion of both of its faces provided with a set of spaced horizontally extending grooves each gradually increasing in depth towards a side edge of the base, said base further having one side edge provided with spaced transversely disposed connecting grooves each gradually increasing in depth from its center towards each end and merging into a pair of horizontal grooves each on opposite faces of the base, said base further having its other side edge provided with spaced inclined connecting grooves gradually increasing in depth from the center thereof towards each end and each extending at an acute angle with respect to a lower marginal groove on one face and merging into an upper marginal groove on the other face of the base, a single length of wire extending through said horizontal,

transverse and inclined grooves and further extending transversely of each face of the base thereby providing spaced ribs, said wire having inter-engaging portions for connecting it together at the upper portion of the base, and means for connecting the wire to one side edge of the base at the lower end thereof.

2. A washboard comprising a pair of legs, a rubbing element arranged therebetween and secured therewith, a transverse strip secured to the outer and the inner face of said element at the upper portion thereof, means arranged between and connected with the legs and extending into the top edge of said element and in connection with said strips providing a pair of soap holders, each of said strips having its inner face formed with a plurality of vertically disposed spaced grooves, and said element having each of its faces at its upper portion provided with a plurality of vertically disposed tapered grooves registering with the grooves of the strips to provide a plurality of drainage openings at the bottom of each of the soap holders.

In testimony whereof, I affix my signature hereto.

OCTAVER J. HEBERT.
